UNITED STATES PATENT OFFICE.

LORENZ MAISEL, OF MADISON, WISCONSIN, ASSIGNOR TO BURGESS BATTERY COMPANY, OF MADISON, WISCONSIN, A CORPORATION OF WISCONSIN.

BATTERY HAND-LAMP.

1,354,323.

Specification of Letters Patent. Patented Sept. 28, 1920.

Application filed August 26, 1918. Serial No. 251,389.

To all whom it may concern:

Be it known that I, LORENZ MAISEL, citizen of the United States, residing at Madison, in the county of Dane, State of Wisconsin, have invented certain new and useful Improvements in Battery Hand-Lamps; and I do hereby declare the following to be a full, clear, and exact description of the invention, such as will enable others skilled 10 in the art to which it appertains to make and use the same.

The present invention has reference to battery hand lamps, and primarily to lamps of the type in which a controlling member 15 or switch mounted in a housing attached to the lamp case and electrically connected with one conductor, is movable in the housing into and out of engagement with the other conductor, the two conductors having 20 electrical connection with the lamp reflector and the battery, respectively.

The invention resides in the provision of certain improvements, hereinafter fully described, relating notably to the aforesaid 25 controlling member or switch, which is so constructed and arranged as to enable it to be readily and quickly manipulated, and to be moved at the will of the operator into either temporary or binding engagement 30 with its co-acting conductor, or into binding engagement with the case, the binding engagement in both instances serving to lock the switch in either of its two positions, so that accidental displacement therefrom is 35 prevented. Moreover, the mounting of the switch is such that its repeated movement from one position to the other does not result in the rubbing or grinding of fine particles of metal into the case, as may happen 40 with lamps of other types, the metallic trail thus formed frequently having an injurious action upon the battery.

According to the invention, the improved 45 switch consists of a rotating nut or its equivalent, which is carried by a threaded pin mounted in the housing above referred to. This pin is arranged parallel with the axis of the lamp, and the nut is adapted to move thereon in either direction, consequent upon 50 its rotation, so that it may be brought into and out of contact with the out-turned end of the associated conductor, the opposite end of which is electrically connected with the reflector. The other conductor is electrically 55 connected with the housing and, hence,

with the nut or switch, so that when the latter engages the terminal of the first-mentioned conductor, the circuit will be closed and the lamp lighted. By arranging the carrier pin in the manner specified, the opposite faces of the nut will be disposed transversely of the axis of the lamp, from which it follows that a wiping engagement between said faces and the contact strip terminal and case is assured, thereby effecting the retention of the nut in such engagement for the purposes stated, although the nut may, of course, have a momentary engagement only with said terminal if the lighting of the lamp is to be merely temporary.

The accompanying drawing shows one form which a lamp constructed in accordance with the invention may take; but it is to be understood that no limitation to the precise structural features of such form, either singly or in combination, is contemplated, excepting in so far as may be necessitated by the language of the appended claims, since the invention is susceptible of appreciable modification and change within 80 the scope of said claims, and since parts and features of the invention as disclosed may be used independently of one another and in other and different environments.

In said drawing:

Figure 1 is a side elevation of the improved lamp;

Fig. 2 is a vertical section;

Fig. 3 is an end view of the case of the lamp; and

Fig. 4 is a vertical section of a slight modification, or development of the invention.

Referring more particularly to the drawing, the structure shown therein embodies a cylindrical case 1, which, in the form illustrated in Figs. 1 and 2, is constructed of fiber, or other suitable insulating material, but which may be made of metal, as represented in Fig. 4. In either instance, the case 100 is provided at one end with a threaded metal collar 2, over which may be screwed a threaded cap 3 arranged to hold the lens 4 and reflector 5 against the end of the case. The incandescent lamp or bulb 6 is fitted in 105 the reflector in the usual way, and has a projecting contact 7 for engagement with the adjacent terminal 8 of the battery 9, the latter usually comprising a plurality of dry cells arranged end to end in series connec- 110

tion within a pasteboard tube. The zinc container of the lowermost cell is engaged by a coiled spring 10, which is carried by the threaded cap 11 at the bottom of the case and serves to hold the battery firmly against the lamp terminal 7, said spring being included in the electrical connections between the aforesaid zinc container and the switch or controlling member 13, herein-
10 after described, which connections in the form shown in Figs. 1 and 2 also comprise a threaded metal collar 12 engaged by said cap 11. All of the parts thus far referred to, with the exception of the switch 13, are, 15 or may be, in the main, of conventional form.

The afore-mentioned switch 13 embodies the most important features of the invention, as previously stated, and, in its preferred form, consists of a knurled wheel or nut, or equivalent device, which is rotatably mounted on a threaded pin 14, which is itself mounted in a metal housing 15, suitably secured by studs 16 to the case 1. The housing comprises a semi-cylindrical boss 17, which is cut away transversely at its center, as at 18, so as to provide a space or opening through which the outer portion of the nut projects to permit its manipulation, the inner portion of the nut extending in like manner into an opening 19 in the case. The pin 14 is supported at its opposite ends in apertures in the end walls of the boss 17 in such a way as to prevent it from turning 25 with the nut when the latter is rotated. Consequently, when the said nut is turned in one direction or the other, it will be caused to move longitudinally of the pin, and, hence, to approach one or the other of the end walls 30 of the openings 18 and 19. The opening 19 in the case is, however, of less length than the housing opening 18, so that contact of the nut with the walls of the former opening is thereby permitted, but is prevented from 35 taking place with those of the latter opening.

The switch nut is utilized to make and break electrical connection between a pair of conductors shown in Figs. 1 and 2 as consisting of metal strips 20 and 21, which are 40 arranged longitudinally of the fiber case against the inner surface thereof and are respectively connected with the collar 12 and reflector 5. In Fig. 4, where a metal case is disclosed, only the upper strip 21 is utilized, 45 the case itself forming the other conductor; and in that instance the said upper strip is insulated from the case by an intermediate strip 22 of rubber, fiber or similar material, and the reflector is similarly insulated by 50 means of a rubber or fiber ring 23 which is interposed between the out-turned or flanged supporting edge 24 of the reflector and the in-turned upper edge 25 of the collar 2. The lower strip 20, when used, has its lower end 55 bent at 26 around the lower edge of the case

and inserted between the latter and the collar 12, and its upper end fastened to one of the studs 16 which secure the housing to the case. The upper strip 21, in like manner, has its lower end 27 bent around the upper 70 edge of the opening 19, and its upper end 28, in the form shown in Figs. 1 and 2, is turned or bent slightly outward so as to extend partly across the upper edge of the case, the latter end being introduced between the 75 aforesaid edge of the case and the supporting edge 24 of the reflector, which rests directly on the case edge in the usual manner. In this way, the required electrical contact between the reflector and the upper strip is 80 maintained, while at the same time the terminal 28 of said strip is prevented from touching the metal collar 2, the upper edge of the latter being spaced slightly below the edge of the case for that purpose, so that 85 short-circuiting is thus avoided. The stud 29 employed to fasten the said strip in place has its outer end countersunk in the fiber out of contact with collar 2 for the same reason. In the modified combination illustrated in Fig. 4, the upper end of the single conducting strip 21 is bent inwardly so as to contact with the reflector, as indicated at 30, and thus complete the required electrical connection, the fastening stud 31 for said 95 strip being insulated in the manner shown.

From the foregoing, it will be apparent that when the lamp is grasped in the hand in the ordinary way, the switch nut 13 can be readily turned by a simple movement of the 100 thumb of the operator, such rotation causing it to move toward either the bent terminal 27 of the conductor 21 or the lower edge of the case opening 19, according to its direction. The engagement of the nut with the 105 aforesaid terminal completes the circuit through the lamp, as will be understood, with the result that the bulb becomes illuminated, such engagement being either of a temporary or a permanent character according as the operator may desire. In the latter instance, the nut is caused to wipe against, and thereby lock itself in binding engagement with the terminal; whereas in the 110 former instance, it is merely caused to touch the terminal and is then moved away from it. As soon as the contact between the nut and the terminal of the conductor ceases, the circuit will be opened, and if it is desired to thereafter insure protection against accidental closing of the circuit, as when the lamp is being carried in the pocket or in a piece of luggage, this may be effected by turning the nut far enough to bring it into binding engagement with the lower edge of 115 the opening 19, in which position it will be locked by the friction exerted upon it. It is also to be observed that the nut is disposed at all times within the opening 19 in the fiber case, and is, moreover, spaced from 120 125 130

the pasteboard wrapper of the battery, so that its repeated manipulation cannot cause a trail of fine metal particles to be ground into either of the parts specified which might 5 occasion some injury to the battery.

I claim as my invention:

1. In a battery hand lamp, the combination, with a battery case having a pair of conductors, and a lamp; of a device on said 10 case for establishing electrical connection between said conductors to light said lamp, embodying a member rotatable on an axis eccentric to said case into and out of engagement with one conductor and adapted to bind laterally against that conductor when engaged therewith to maintain such engagement.

2. In a battery hand lamp, the combination, with a battery case having a pair of 20 conductors, and a lamp; of a device for establishing electrical connection between said conductors to light said lamp, embodying a member having a combined rotary and lateral movement into and out of engagement with one of them, said member being mounted on said case in position to be manipulated by the hand in which the case is held.

3. In a battery hand lamp, the combination, with a battery case having a pair of 30 conductors, of a lamp; of a device for establishing electrical connection between said conductors, to light said lamp, embodying a member having a combined rotary and lateral movement into and out of engagement with one conductor and adapted to bind against that conductor when engaged therewith to maintain such engagement, said member being mounted on said case in 35 position to be manipulated by the hand in which the case is held.

4. In a battery hand lamp, the combination, with a battery case having a pair of conductors, and a lamp; of a device on said 45 case for establishing electrical connection between said conductors to light said lamp, embodying a housing, a pin mounted in said housing; and a rotatable member carried by said pin and adapted to move into 50 and out of engagement with one conductor.

5. In a battery hand lamp, the combination, with a battery case having a pair of conductors, and a lamp; of a device on said case for establishing electrical connection 55 between said conductors to light said lamp, embodying a housing, a threaded pin mounted in said housing, and a nut rotatably mounted on said pin and adapted to travel thereon into and out of binding engagement with one conductor.

6. In a battery hand lamp, the combination of a case having an opening formed therethrough; a lamp carried by said case; a conductor within said case; and a device 65 mounted on the exterior of the case for

completing an electric circuit through said conductor to light said lamp, embodying a member projecting through said opening into the interior of the case and mounted for rotary movement into and out of engagement with said conductor. 70

7. In a battery hand lamp, the combination of a case having an opening therein; a lamp carried by said case; a conductor within said case; and a device for completing an electric circuit through said conductor to light said lamp embodying a member projecting through said opening into the case, said member being mounted for rotary movement in one direction into engagement with one conductor, and for rotary movement in the opposite direction into binding engagement with the adjacent end wall of said opening. 75

8. In a battery hand lamp, the combination of a case having an opening therein; a lamp carried by said case; a conductor within said case having its terminal extending outwardly through said opening; and a device for completing an electric circuit 80 through said conductor to light said lamp, embodying a member projecting inwardly through said opening, said member being mounted for rotary movement in said opening into and out of binding engagement 85 with said terminal.

9. In a battery hand lamp, the combination of a case having an opening therein; a lamp carried by said case; a conductor within said case having its terminal extending outwardly through said opening; and a device for completing an electric circuit 90 through said conductor to light said lamp, embodying a member projecting inwardly through said opening, said member being mounted for rotary movement in one direction 95 in said opening to bring it into binding engagement with said terminal, and for rotary movement in the opposite direction in said opening to bring it into binding engagement with the adjacent end wall of the opening. 100

10. In a battery hand lamp, the combination of a case having an opening therein; a lamp carried by said case; a battery within the case; a housing attached to the side of the case and electrically connected with the battery, said housing having an opening in line with the first-named opening; a conductor within said case having its terminal disposed adjacent said first-named opening; a threaded pin mounted in said housing; and a rotatable member carried by said pin to travel thereon in either direction, said member having a portion thereof 115 projecting outwardly through the second-named opening for manipulation, and an opposite portion projecting inwardly through the first-named opening to be brought into contact with said terminal to 120

125

close the circuit through said lamp when said member is turned in the proper direction.

11. In a battery hand lamp, the combination of a case having an opening therein; a lamp carried by said case; a housing attached to the side of the case and having an opening in line with the first-named opening; a conductor within said case having 10 its terminal disposed adjacent said first-named opening; a threaded pin mounted in said housing; and a rotatable member carried by said pin to travel thereon in either direction, said member 15 having a portion thereof projecting outwardly through the second-named opening for manipulation, and an opposite portion projecting inwardly through the first-named opening to be brought into contact with said 20 terminal to close the circuit through said lamp when said member is turned in one direction and to be brought into binding engagement with the adjacent end wall of said first-named opening when turned in the opposite 25 direction.

12. In a battery hand lamp, the combination of a case; a reflector therein; a bulb fitted in said reflector and having an exposed terminal; a lens fitted on said reflector; a cap for holding said lens and reflector in place; a battery in said case having a terminal to engage the lamp terminal; a spring within said case acting against the battery to hold said terminals in such engagement; a cap fitted on said case and carrying said spring; a pair of conductors disposed longitudinally within said case, one having electrical connection at its outer end with the reflector, and the other having electrical connection at its outer end with the second-named cap, said spring maintaining electrical connection between said second-named cap and the other terminal of the battery; a housing mounted on the side of the case and electrically connected with the inner end of said other conductor; and a contact member mounted in said housing for rotary movement about its axis into engagement with the inner end of the first-named 40 conductor, thereby to establish electrical connection between said conductors.

13. In a battery hand lamp, the combination of a casing, batteries and a lamp therein, a housing mounted on the side of said casing and connected with said batteries, a conductor connected with said lamp and terminating within said housing and a contact

member mounted in said housing for rotary movement about its axis and for lateral movement in the direction of its axis into 60 and out of contact with that part of said conductor which is beneath said housing.

14. In a battery hand lamp, the combination, with a battery case having a pair of conductors, at least one of which is in the 65 form of a narrow metal strip provided with a laterally bent terminal, and a lamp; of a device on said case for establishing electrical connection between said conductors to light the lamp, said device embodying a member 70 rotatable into and out of engagement with said bent terminal about an axis eccentric to the axis of said case.

15. In a battery hand lamp, the combination, with a battery case having a pair of 75 conductors, at least one of which is in the form of a narrow metal strip provided with a laterally bent terminal, and a lamp; of a device on said case for establishing electrical connection between said conductors to 80 light the lamp, said device embodying a member rotatable about its axis and adapted to wipe against said bent terminal during the course of such rotation to lock it in engagement therewith.

16. In a battery hand lamp, the combination, with a battery case having a pair of conductors, at least one of which is in the 85 form of a narrow metal strip provided with a laterally bent terminal, and a lamp; of a 90 device on said case for establishing electrical connection between said conductors to light the lamp, said device embodying a housing adjacent which said bent terminal is located, and a member mounted in said 95 housing for rotary movement about its axis into and out of engagement with the said terminal.

17. In a battery hand lamp, the combination, with a battery case having a lamp and 100 a pair of conductors, at least one conductor being in the form of a narrow metal strip provided with a bent terminal projecting through the case; of a device for establishing electrical connection between said conductors to light the lamp, said device embodying a member mounted on the exterior of said case in position to be manipulated by the hand in which the lamp is grasped, and adapted to rotate into and out of engagement with said bent terminal about an axis eccentric to the axis of the case.

In testimony whereof I affix my signature.
LORENZ MAISEL.

It is hereby certified that in Letters Patent No. 1,354,323, granted September 28, 1920, upon the application of Lorenz Maisel, of Madison, Wisconsin, for an improvement in "Battery Hand-Lamps," an error appears in the printed specification requiring correction as follows: Page 3, line 31, claim 3, first occurrence, for the word "of" read *and*; and that the said Letters Patent should be read with this correction therein that the same may conform to the record of the case in the Patent Office.

Signed and sealed this 30th day of November, A. D., 1920.

[SEAL.]

L. B. MANN,

Acting Commissioner of Patents.

Cl. 240—8.5.
